UNITED STATES PATENT OFFICE.

HUGO C. RAIBER, OF PITTSBURGH, PENNSYLVANIA.

RECEIVER-HOLDER FOR TELEPHONES.

1,073,708.

Specification of Letters Patent. Patented Sept. 23, 1913.

Application filed October 19, 1912. Serial No. 726,773.

To all whom it may concern:

Be it known that I, Hugo C. RAIBER, a citizen of the United States of America, residing at Pittsburgh, in the county of Allegheny and State of Pennsylvania, have invented certain new and useful Improvements in Receiver-Holders for Telephones, of which the following is a specification, reference being had therein to the accompanying drawing.

This invention relates to a receiver holder for telephones, and the primary object of my invention is to furnish a telephone with novel receiver holders that can be easily and quickly swung into position at a person's ears, the holders releasing the ordinary switch arm or hook whereby a conversation can be carried on over the telephone.

Another object of this invention is to provide a telephone attachment that permits of two receivers being used in connection with the same, thus facilitating a person in using the telephone, particularly when the person has affected hearing.

A further object of this invention is to provide a telephone attachment of the above types that is applicable to various types of telephones, especially a desk telephone, the attachment being easily secured to the pedestal of a telephone whereby it will be in position for instant use.

A still further object of this invention is to provide a telephone attachment that is inexpensive to manufacture, free from injury by ordinary use and highly efficient for overcoming the necessity of holding a receiver to the ear by the hand.

With the above and other objects in view the invention resides in the novel construction, combination and arrangement of parts to be hereinafter specifically described and then claimed.

Reference will now be had to the drawing, wherein:

Figure 1 is a side elevation of the telephone attachment, partly broken away, Fig. 2 is a front elevation of the same, and Fig. 3 is a perspective view of a portion of the attachment.

Further describing my invention in detail with reference to the accompanying draw-

ing, wherein like numerals denote corresponding parts throughout: 1 denotes a pedestal of a desk telephone and mounted upon said pedestal is a cylindrical clamp 2, 55 retained thereon by screws 3 or other fastening means. A yieldable sleeve 4, preferably made of felt is interposed between the clamp and the pedestal to prevent the pedestal from being injured. The clamp 2 has diametrically opposed trunnions or pins 5 and pivotally mounted thereon are the apertured arms 6 of curved receiver holders 7. The arms 6 are arranged in parallelism and connected by an integral strap 8 whereby said arms can be moved in unison. One of the arms has a notch 9 with the walls thereof beveled, as at 10, whereby the arm can be placed in engagement with the switch arm or hook 11 of a telephone. It is this notched 70 arm that retains the hook in a lowered position, similar to the function heretofore performed by an ordinary receiver, the hook in a lowered position closing the talking circuit. When the notched arm is swung out 75 of engagement with the hook the hook is released and immediately establishes a talking circuit. The holders 7 are curved to provide clearance for the head and at the end of each holder is a receiver 12. The 80 receivers are diametrically opposed and can be easily placed against the ears.

The receiver holders can be stamped from a single piece of light and durable metal and the entire attachment finished to harmonize with the metallic fittings of the telephone.

While in the drawing there is illustrated a preferred embodiment of the invention, it is to be understood that the structural elements are susceptible to such variations and modifications as fall within the scope of the appended claim.

What I claim is:

In a receiver holder, a clamp adapted to 95 be secured to the pedestal of a telephone and provided with oppositely disposed trunnions, a pair of vertically disposed parallel arms pivotally mounted at their lower ends upon said trunnions and each having its 100 upper ends terminating in an outwardly curved receiver holder, a strap integral with

said arms for maintaining them in parallel relation, and one of said arms having its inner edge provided with a notch formed with beveled walls, said notch permitting its 5 respective arm to be placed in engagement with the switch arm of a telephone for maintaining it in a lowered position.

In testimony whereof I affix my signature in the presence of two witnesses.

HUGO C. RAIBER.
